APPARATUS FOR THE CONCENTRATING OF
MINERALS BY MEANS OF FROTH FLOTA-
TION.

Rudolf Wunsch, Milan, Italy

Application July 20, 1949, Serial No. 105,848.
In Italy July 21, 1948

8 Claims. (Cl. 209—169)

1

It is the object of the present invention to provide such improvements in or relating to apparatus for carrying out ore concentration by the froth flotation process, as may result in apparatus of a new type or be applied with apparatus of other types already existing or of new types that might be developed and proposed. Flotation machines operating by mechanical agitation are known wherein aeration of the pulp is provided by a rotating impeller in an agitating compartment divided by a vertical wall from the froth separating compartment, said wall having in its upper portion a port through which the pulp enters into a frothing chamber having a hopper shape, the so-called spitzkasten. At the bottom of this spitzkasten there is a pipe for returning the pulp to the rotor or impeller in the agitating compartment.

It was found that these impellers provide maximum aeration of the pulp if they carry radial blades revolving under and close to a flange; however, this type of impeller requires much power for maintaining sufficient circulation of the pulp between agitating compartment and spitzkasten. On the other hand, if the impeller is provided with curved blades like those of a centrifugal pump, power requirements diminish, but aeration also diminishes considerably. The attempt was made to eliminate this inconvenience by providing a double rotor equipped with both curved blades and radial blades, the pulp entering into the double rotor from top and passing partly through the radial blades and partly through the curved blades, so that sufficient aeration and circulation is attained.

The present invention provides for two separate rotors in the agitating compartment; a lower rotor at the bottom of the agitating compartment, shaped like the rotor of a centrifugal pump; and an upper rotor carrying radial blades. The connection between these two rotors is such that the lower rotor forces the whole pulp, both the pulp fed from the preceding cell and the pulp circulating inside the compartments to pass through the upper rotor, in order to attain perfect aeration. It is therefore a specific object of the present invention to provide a froth flotation apparatus in which the agitating compartment and the spitzkasten are adjacent one another and in which the agitating compartment is divided into an upper aerating and agitating compartment and a lower pumping and agitating compartment by a horizontal partition having a single opening therein constituting the only communication between these upper and

2

lower compartments and in which in each compartment impeller means are arranged, in the lower compartment said means constituting a pump means including a substantially enclosed rotor and in the upper compartment an impeller constituting a combined aerating and agitating impeller and in which means are provided for leading the pulp from the spitzkasten to and feeding the same centrally of the rotor in the lower compartment and a casing surrounds the impeller in the upper compartment, extends upwardly therewithin, terminates at least adjacent the pulp level and is in communication with the air that is to aerate the pulp. The arrangement is such that with a controllable opening between the upper compartment and the spitzkasten open and pulp fed to the lower compartment the circulation of pulp is effected and all pulp entering the lower compartment must pass through the single opening in the horizontal partition into the sphere of action of the impeller in the upper compartment and which latter impeller is operative to draw air into the casing to mix the same with the pulp.

25 It is a further and more specific object to incorporate stationary deflector means in the lower pumping compartment that is positioned subjacent the aperture in the horizontal partition and has a surface which in vertical cross-section and in combination with the undersurface of the horizontal partition defines a Venturi type throat so as to accelerate pulp flow through the single opening in the horizontal partition into the sphere of action of the upper impeller.

30 35 It is an additional specific object to incorporate a downwardly open bell mouth flange and to mount the rotor of the pump in position to rotate closely adjacent this flange and provide means for feeding new pulp and means for leading pulp from the spitzkasten centrally of this bell mouth flange so that all pulp is fed to the rotor of the pump centrally thereof.

40 Further and more specific objects will be apparent in the following detailed description.

An embodiment of the present invention is illustrated in the accompanying drawings, in which:

45 Figure 1 is a longitudinal sectional view thereof with some parts shown in elevation;

50 Figure 2 is a top plan view of the rotor in the pumping compartment and illustrating the curvature of the blades thereof; and

55 Figure 3 is a vertical sectional view through the stationary deflector and the bell-mouth flange depending therefrom and located in the

pumping compartment and taken at right angles to the illustration thereof in Figure 1 and looking toward the left in Figure 1.

In the arrangement illustrated the fresh pulp flowing from a ball mill or pulp flowing from a preceding cell passes through pipe 1 and into the diffusor 2 into which circulating pulp returned from the spitzkasten 20 also enters through pipe 18. Under and closely adjacent the bell mouth flange of the diffusor there is arranged the bottom rotor 3 which has curved blades and is driven by the shaft 4. As shown in the drawing this rotor 3 is substantially enclosed since the horizontal disc supporting the same is imperforate and the respective pulp conduits constituting the pipes 1 and 18 feed the pulp centrally within the bell mouth flange so that the pulp is fed centrally of this rotor. Thus the cooperation of the rotor with the flange in the manner of pulp feed defines a centrifugal pump. The pulp pumped through rotor 3 passes through the central circular port or aperture in the horizontal partition 6. Subjacent this aperture there is arranged the deflector baffle 7 which has a spherical upper surface and therefore, the whole of the pulp must pass at considerable speed through said central circular port to flow centrally of and beneath the lower part of a double rotor provided with upper and lower radial blades 9 and 8 respectively and driven by the shaft 10. This double rotor revolves within a cylinder 12 having an opening in the wall thereof directed toward the grid 15 controlling pulp flow into the spitzkasten. Since the pulp raised by the bottom rotor enters the sphere of action of lower part of the double rotor at considerable speed owing to the shape and position of the deflector baffle 7, this lower part of the rotor, having the radial blades 8, consumes little power because its task is not to accelerate the pulp but only to aerate it and direct its flow into the spitzkasten.

As a matter of fact, experiments on an industrial scale have evidenced that a considerable reduced speed of operation of the radial-bladed rotor is possible while maintaining active aeration of the pulp. The upper part of the double rotor also carries radial blades 9 turning under a flange formed by the conical vessel 11 and this part serves to aerate the overflow, which is adjustable at will by adjusting the position of the gate 13 through which the pulp is discharged to the subsequent cell. The level of the pulp in the spitzkasten 20 can be adjusted at will by raising or lowering the grid 15 by means of the hand wheel 16. The grid 17 in the spitzkasten serves to calm down the pulp impelled by the double rotor. In order to ensure rapid progress of the froth toward the discharge scraper 22, a movable apron 21 is so arranged as not to restrict the frothing surface.

It is therefore clear that this invention provides a froth flotation apparatus comprising tank means which includes a vertical partition and a horizontal partition 6 extending from one side of and intermediate the ends of the vertical partition. These two partitions divide the tank means into three compartments comprising an aerating and agitating compartment above the horizontal partition, a pumping and agitating compartment beneath this horizontal partition and a spitzkasten on the opposite side of the vertical partition. The horizontal partition is provided with a single central opening therein affording communication between the pumping and agitating compartment and the aerating and agitating compartment. The vertical partition has an

opening therein above the horizontal partition which is controllable and which provides a communication between the upper aerating and agitating compartment and the spitzkasten. A pump means is provided in the pumping compartment and includes a substantially enclosed rotor and in addition the conduits 1 and 18 are provided which feed new pulp and pulp contained in the spitzkasten centrally of the bell mouth flange beneath which the rotor 3 rotates so that all pulp is introduced centrally of this rotor so that when the same is operating it draws the pulp into the center thereof to agitate the same and force the pulp to flow through the single central opening in the horizontal partition. When the pump is in operation therefore, a pulp circuit is afforded between the three compartments. Within the upper aerating and agitating compartment there is provided a cylindrical casing of greater diameter than and surrounding the single opening in the horizontal partition. This casing extends upwardly from the horizontal partition and terminates at least adjacent the pulp level that is maintained in the upper aerating and agitating compartment in accordance with the adjustment of the gate 13. The casing is open to the air, that is to aerate the pulp and in the position of adjustment shown this casing terminates slightly beneath the pulp level in the upper compartment so that pulp cascades into the casing in a thin veil. This casing 12 is provided with an opening in the wall thereof that faces the opening providing communication with the spitzkasten. An aerating and agitating impeller is mounted within the casing for rotation on a vertical axis. This impeller includes a horizontal disc having upper and lower sets of radial blades with the lower radial blades disposed closely adjacent the horizontal partition. The operation of this impeller sets up a suction action as regards the casing so as to suck air into the casing and beat the same into the pulp. The lower blades are impinged upon by the pulp forced by the pump out of the lower compartment which action enables the operation of the upper impeller at reduced power and which upper impeller will accelerate the agitation of pulp initially agitated in the pumping compartment and thoroughly mix air with all the pulp that flows through the central aperture in the horizontal partition.

As shown in the drawings the deflector means 7 is positioned coaxially of and subjacent the single opening in the horizontal partition. This deflector constitutes a body having a spherical upper surface so as to provide a channel of decreasing or reducing size or width between the outer limits of the deflector and the opening. In other words any vertical cross-section taken through deflector 7 and the horizontal partition defines a space between the partition and the upper surface of the deflector that narrows in width toward the central opening to provide a Venturi type throat to accelerate pulp flow through said single opening, as shown in Figures 1 and 3.

The arrangement therefore provides froth flotation apparatus in which all new pulp must be subjected to the action of the pumping and agitating rotor and the upper aerating and agitating impeller and additionally any pulp that has passed through these two mechanisms and flow into the spitzkasten positively recirculated at least once through both of these impeller means before it can overflow through the gate 13 to the next cell.

As is clear from the showing in Figures 1 and 3, the means for leading pulp from the spitskasten to and feeding the same centrally of the rotor includes the conduit 18 in communication with the spitskasten beneath the horizontal partition and extending within the pumping compartment. The stationary deflector body 7 mounted beneath the single central opening in the horizontal partition has an aperture therethrough in communication with the conduit 18. This aperture terminates in a downwardly directed opening above the rotor. The raw pulp inlet conduit 1 also extends within the pumping compartment. The deflector body has another aperture therethrough that terminates in a downwardly directed opening above the rotor. This aperture communicates with conduit 1. An annular depending bell-mouth flange is embodied with the body for partly delimiting and surrounding both the said openings. The rotor rotates closely adjacent this flange so that the pulp feeds centrally thereof from both said openings.

The two rotors may be driven by separate shafts or by a single shaft. Of course, the invention may be embodied in a manner different from that illustrated, without departing from the scope of the invention as defined in the appended claims.

Having now particularly described and ascertained the nature of my said invention and in what manner the same is to be performed, I declare that what I claim is:

1. In a froth flotation apparatus means defining an agitation compartment and a spitskasten both adapted to contain pulp, a vertical wall separating the same, a horizontal partition dividing the agitating compartment into an upper aerating and agitating compartment and a lower pumping and agitating compartment, said horizontal partition having only a single opening therein, said wall having an opening therethrough above the horizontal partition and providing communication between said upper compartment and said spitskasten, pump means within the pumping compartment including a substantially enclosed rotor, means for leading pulp from the spitskasten to and feeding the same centrally of the rotor, a cylindrical casing surrounding said opening in the horizontal partition and extending upwardly within said upper compartment and terminating at least adjacent the pulp level therein, said casing being in communication with the air that is to aerate the pulp and having an opening therein adjacent the horizontal partition, a combined aerating and agitating impeller within the casing and rotatable therein at the level of said last mentioned opening, and operative to draw air into the casing to mix same at least with the pulp forced through said single opening by said pump rotor.

2. Froth flotation apparatus comprising tank means including a vertical partition and a horizontal partition extending from one side of and intermediate the ends of the vertical partition, said two partitions dividing the tank means into three compartments comprising an aerating and agitating compartment above the horizontal partition, a pumping and agitating compartment beneath said horizontal partition, and a spitskasten on the opposite side of the vertical partition, said horizontal partition having a single central opening therein providing communication between the pumping and agitating compartment and the aerating and agitating compartment, said ver-

tical partition having an opening therein above the horizontal partition to provide communication between the aerating and agitating compartment and the spitskasten, a pump means in the pumping compartment including a substantially enclosed rotor, means for feeding pulp into the pumping compartment including means for introducing pulp to said rotor centrally thereof, means for leading pulp from said spitskasten to the means for introducing pulp centrally of the rotor so that operation of the rotor draws pulp into the center thereof to agitate the same and force pulp through the single central opening in the horizontal partition from whence it passes through said aerating and agitating compartment and flows into said spitskasten for recirculation and froth separation, a cylindrical casing surrounding the single central opening in the horizontal partition, extending upwardly thereof and terminating at least adjacent the pulp level in the aerating and agitating compartment, said casing being open to the air, and said casing further having an opening above the horizontal partition and directed toward the opening providing communication with the spitskasten, an aerating and agitating impeller mounted within said casing including blades movable closely adjacent said horizontal partition, said agitating impeller drawing air into the casing to mix with the pulp and further accelerating the agitation of the pulp initially agitated in the pumping compartment so as to thoroughly mix air with all pulp flowing through the single central opening in the horizontal partition.

3. Froth flotation apparatus comprising tank means including a vertical partition and a horizontal partition extending from one side of and intermediate the ends of the vertical partition, said two partitions dividing the tank means into three compartments comprising an aerating and agitating compartment above the horizontal partition, a pumping and agitating compartment beneath said horizontal partition, and a spitskasten on the opposite side of the vertical partition, said horizontal partition having a single central opening therein providing communication between the pumping and agitating compartment and the aerating and agitating compartment, said vertical partition having an opening therein above the horizontal partition to provide communication between the aerating and agitating compartment and the spitskasten, a pump means in the pumping compartment including a substantially enclosed rotor, means for feeding pulp into the pumping compartment including means for introducing pulp to said rotor centrally thereof, means for leading pulp from said spitskasten to the means for introducing pulp centrally of the rotor so that operation of the rotor draws pulp into the center thereof to agitate the same and force pulp through the single central opening in the horizontal partition from whence it passes through said aerating and agitating compartment and flows into said spitskasten for recirculation and froth separation, a cylindrical casing surrounding the single central opening in the horizontal partition extending upwardly thereof and terminating at least adjacent the pulp level in the aerating and agitating compartment, said casing being open to the air, and said casing further having an opening above the horizontal partition and directed toward the opening providing communication with the spitskasten, an aerating and agitating impeller mounted within said casing, and including a horizontal disc having upper and lower sets of radial blades, and

with the lower radial blades disposed closely adjacent the horizontal partition, said agitating impeller drawing air into the casing to mix with the pulp and further accelerating the agitation of the pulp initially agitated in the pumping compartment so as to thoroughly mix air with all pulp flowing through the single central opening in the horizontal partition.

4. Froth flotation apparatus as defined in and by claim 3 and including a stationary deflector positioned coaxially of and subjacent the single central opening in the horizontal partition, said deflector constituting a body having an upper surface defining in vertical cross-section and in cooperation with horizontal partition a conduit of reducing size with the narrowest size being adjacent the said single central opening so as to provide a Venturi type throat through which all pulp contained in the pumping and agitating compartment must pass and said throat accelerating pulp flow to the upper aerating and agitating compartment.

5. Froth flotation apparatus as defined in and by claim 3 in which the cylindrical casing surrounding the single central opening in the horizontal partition is of greater diameter than the diameter of said single central opening and coaxially disposed with respect thereto, and said casing having interiorly thereof over at least a portion of its length means defining a conical surface diminishing in diameter in a direction from the top to the bottom of the casing and terminating in spaced relation to the upper surface of said horizontal partition and defining a central axial opening in the cylindrical casing, said casing terminating at least slightly beneath the pulp level in the aerating and agitating compartments so that pulp cascades over the same and through the said central axial opening, horizontally disposed flange portions extending between the lower terminal end of the conical surface and the inner surface of said casing, and the upper radial blades of said aerating and agitating impeller being rotatable immediately subjacent the said horizontal flange portions so that when said agitating and aerating impeller is rotating air is sucked through the casing together with the pulp cascading thereinto and which pulp and air are thoroughly mixed with the pulp flowing from the lower pumping and agitating compartment through the said single opening in the horizontal partition.

6. A froth flotation apparatus as defined in and by claim 1 in which the means for leading pulp from the spitskasten to and feeding the same centrally of the rotor includes a conduit in communication with the spitskasten beneath said horizontal partition and extending within the

pumping compartment, a stationary deflector body mounted within the pumping compartment subjacent the single central opening and having an aperture therethrough with which said conduit communicates, said aperture terminating in a downwardly directed opening, a depending annular bell mouth flange embodied with said body and surrounding said last mentioned opening, and said pump rotor being rotatable closely subjacent said bell-mouth flange and receiving pulp centrally thereof from said downwardly directed opening.

7. A froth flotation apparatus as defined in and by claim 6, and further including a raw pulp inlet conduit extending within said pumping compartment and terminating therewithin, said stationary body having another aperture therethrough terminating in a downwardly directed opening, said last mentioned aperture being in communication with said raw pulp inlet conduit at one end and through said downwardly directed opening with said bell-mouth flange at the other.

8. A froth flotation apparatus as defined in and by claim 7, and in which said stationary body is mounted coaxially beneath said single opening in the horizontal partition and has a spherical upper surface, the axis of which is coaxial with said opening so that the said upper surface in cooperation with the undersurface of said horizontal partition defines a pulp conduit of reducing width with the narrowest width adjacent said single opening in the horizontal partition thereby accelerating pulp flow into and through said single opening in the horizontal partition.
